ROLLER DRUM SUPPORT FOR A REVOLVER-TYPE GUN

John F. O'Brien, Springfield, Mass., assignor to the United States of America as represented by the Secretary of the Army

Application March 12, 1954, Serial No. 415,989

1 Claim. (Cl. 89—155)

(Granted under Title 35, U. S. Code (1952), sec. 266)

The invention described herein may be manufactured and used by or for the Government for governmental purposes without the payment of any royalty thereon.

My invention relates to a revolver-type automatic weapon and more particularly to a device thereof for supporting a rotatable cartridge drum.

In the usual weapon including five or six cartridge chambers the drum is keyed to an axial shaft journaled in the recoil unit of the weapon for rotation of the chambers to stations spaced correspondingly thereto including a six o'clock station of the chambers immediately adjacent the barrel of the weapon for firing the cartridges therein. The forward bearing of the drum shaft, therefore, must be located immediately above the barrel and the minimum pitch radius of the chambers equals the sum of the radii of the barrel and the drum shaft plus the thickness of a bearing wall therebetween. Hence, the surface of the drum extends above the remainder of the weapon and since the drum is rotatably mounted, it usually overhangs the receiver of the weapon. The diameter of the drum therefore determines the transverse silhouette of the weapon.

In a weapon so arranged, the diameter of the drum is excessive, causing the weapon to present an unnecessarily large silhouette since the thickness of metal between five or even six chambers therein is more than adequate for the strength required to withstand the discharges of cartridges in the chambers. The silhouette of the weapon can be reduced by reducing the pitch diameter of the chambers.

It is, therefore, an object of my invention to provide a revolver-type weapon with a low, narrow, transverse silhouette.

Another object of my invention is to provide a weapon of the kind described having a recoil unit with the cartridge drum thereof rotatable within tangential rollers.

A further object of my invention is to provide the recoil unit of such a weapon with a bearing device for circumferential support of a rotatable cartridge drum.

Further aims and objects of my invention will be evident from the succeeding explanation thereof.

In carrying out my invention, the cartridge drum of a revolver-type automatic weapon is provided with a pair of circumferential bands having bearing surfaces and the recoil unit of the weapon is provided with a housing including bearings for tangential engagement with the bearing surfaces for rotation of the cartridge drum in the housing. A front wall of the housing and a rib of the recoil unit axially position the drum.

For a more complete understanding of my invention, attention is directed to the following explanation and the accompanying drawing in which:

2

Fig. 1 is an elevational view, partly in section, of a revolver-type automatic weapon incorporating my invention;

Figs. 2, 3, 4 and 5 are views along the corresponding lines of Fig. 1; and

Fig. 6 is a perspective view of the recoil unit showing the drum bearings.

According to the drawing, a revolver-type weapon 12 includes a receiver 14 with a recoil unit 16 slidably disposed thereon, by means of feet 17 extending into recesses of the receiver. Recoil unit 16 includes a barrel 18 and a support housing 20 for a drum 22 including chambers 24 and corresponding index rollers 26.

Support 20 is provided with forward and rearward sets of rollers 28 journaled on pins 30 secured in bosses 32 of support 20 by means of needle bearings 34. Drum 22 is provided with a pair of circumferential bands 36 for tangential engagement with bearing rollers 28 and the rollers are disposed to circumferentially restrain the drum 22 in the support. Support 20 is relieved by channels 29 to allow insertion of drum 22.

Drum 22 is restrained forwardly and rearwardly, respectively, by a front wall 38 secured to support 20 by means of bayonet lugs 39 and a stop 40 of recoil unit 16. Barrel 18 is threadably secured to a boss 41 projecting forwardly from front wall 38. The forward ends of chambers 24 are usually provided with obturating sleeves to prevent escape of discharge gases and, forward wall 38 includes a portion 42 for engaging the forward end of drum 22 to retain the sleeves in place during rotation of the chambers. Portions of the wall may include grooves 43 to reduce the weight of the weapon.

A firing pin 44 projects through stop 40 for engagement with the primer of a cartridge 45 chambered in the firing station of chambers 24 aligned with barrel 18.

Recoil unit 16 includes a cylinder 46 having a piston 48 secured to a plunger 50 and the cylinder is connected to the bore of barrel 18 through a passage 52. An actuator 54 slidable with respect to recoil unit 16 on feet 55 is biased by springs 56 in engagement with a rear wall 58 of receiver 14 to a battery position in engagement with plunger 50.

Actuator 54 includes surfaces for engagement with index rollers 26 for reciprocal operation responsive to discharge of firing station cartridges 45 to serially convey chambers 24 to stations including the firing station. Gases from the discharge force piston 48, plunger 50, and actuator 54 rearwardly against springs 56 to rotate drum 22. When the projectile from cartridge 45 leaves barrel 18, the pressure on piston 48 drops and actuator 54 is returned to the battery position by springs 56 aided by the kinetic energy of drum 22.

A shaft 60 is engaged by drum 22 for rotation of a feeder generally shown at 62.

As shown in Fig. 3, chambers 24 may be disposed in a pitch circle for minimum drum wall thickness therebetween to withstand the force of discharge in the firing station. If such a drum were to be supported by a shaft, the shaft would interfere with barrel 18. However, in the device of applicant, the axis of drum 22 coincides with the axis of support 20 and is independent of barrel 18.

Reduction of the diameter of drum 22 from the drum diameters required in prior weapons, results in a decrease of the transverse silhouette of the weapon that is only partially offset by the addition of the drum support.

Also, the drum with the reduced diameter requires less energy for rotation and the weapon is operated with less strain on the component parts.

Although a particular embodiment of the invention has been described in detail herein, it is evident that many variations may be devised within the spirit and scope thereof and the following claim is intended to include such variations.

I claim:

A revolver-type automatic weapon comprising a barrel, 10 a recoil unit for support thereof, a drum having spaced chambers for cartridges, a support for said drum secured to said recoil unit, forward and rearward sets of rollers axially journaled in said support, and a pair of circum-

ferential bands on said drum corresponding to said sets of rollers for engagement therewith for rotational displacement of said chambers.
